MINING MACHINE

Charles A. Pratt, Chicago, Ill., assignor to Goodman Manufacturing Company, Chicago, Ill., a corporation of Illinois

Application June 4, 1932, Serial No. 615,297

21 Claims. (Cl. 262—30)

This invention relates to improvements in mining machines of the type adapted to slide on its bottom on the mine bottom during the cutting operation and has, as one of its principal objects, to provide a new and improved mining machine of the class described particularly adapted for operation in thin seams of coal and arranged with a view towards utmost simplicity, compactness, accessibility, and ease and efficiency in operation.

Other objects of my invention will appear from time to time as this specification proceeds.

My invention may be more clearly understood with reference to the accompanying drawings wherein:

Figure 1 is a top plan view of the device embodying my invention mounted on a self-propelling truck, with parts broken away and in section to more clearly show the details thereof;

Figure 2 is a side elevation of the device embodying my invention mounted on a self-propelling truck;

Figure 3 is a partial enlarged fragmentary longitudinal sectional view of the device embodying my invention;

Figure 4 is a sectional view taken substantially on line 4—4 of Figure 1;

Figure 5 is a sectional view taken substantially on line 5—5 of Figure 1; and

Figure 6 is a sectional view taken substantially on line 6—6 of Figure 1.

Like numerals refer to like parts throughout the various figures.

Referring now in particular to the drawings, the embodiment of my invention illustrated comprises a main frame 10, which forms a support for the cutting and feeding mechanism, and a motor 11 detachably secured to the rearward end of said main frame. A projecting cutter bar 12 is supported by and extends forwardly of said main frame and has a cutter chain 13 guided for movement thereabout in a usual manner. A feed drum 14 is supported on the advance side of said main frame for rotation with respect thereto about an axis disposed transversely thereof for moving the machine about the mine and feeding it into and along the coal face.

The mining machine is adapted to be detachably mounted on a self-propelling truck 15 for movement about the mine on the mine tracks from working place to working place in a usual manner. Said truck is of a usual drop front type and is supported on track wheels 16 and axles 17. Means are provided for driving said truck from

the mining machine motor 11 in a manner which will hereinafter be more fully explained.

Referring now in particular to the details of the motor 11 and one of the novel features of my invention, said motor is herein shown as being an electric motor of a high speed type and includes an armature 18 mounted on a vertically disposed armature shaft 19 enclosed in a split motor casing 23. The motor 11 is provided with two wound field coils 20 which comprise consequent poles therefor, and two salient poles 21 supported within the split motor casing 23. The motor casing 23 is split diagonally in a vertical plane and comprises a forward portion 24 detachably secured to the rearward end of the main frame 10 in a suitable manner; as, for instance, nuts and bolts 25; and a rearward portion 26 detachably secured to the forward portion 24 by means of nuts and bolts in a suitable manner. One of the wound field coils 20 is carried on one side of the forward portion 24 of the motor casing 23 adjacent the retreating side of the mining machine, while one of the salient poles 21 is carried on the inner side of the forward portion 24 forwardly of the armature shaft 19. The other wound field coil 20 is carried on the rearward portion 26 of the motor casing 23 adjacent the advance side of the mining machine, and the other salient pole 21 is carried on the inner side of the rearward portion 26 rearwardly of armature shaft 19. Thus the motor 11 is so arranged that the wound poles of said motor, which are larger than the salient poles, are positioned on opposite lateral sides of the armature 18 and main frame 10. This arrangement retains the minimum dimensions of said motor with respect to the length of the machine and effects a machine of a minimum overall length. This arrangement also facilitates the removal of the rearward portion 26 of the motor casing 23 which permits utmost accessibility to all of the motor parts, and enables the mining machine to be compactly and efficiently arranged.

The motor 11 has been so designed as to be of a minimum vertical height, and the motor casing 23 is constructed as small as possible commensurate with the production of an efficient power unit and determines the height of the machine. Furthermore, said motor is of the high speed type which permits the use of a smaller size motor for the same amount of power usually used on mining machines and accordingly permits the construction of a lower, more compact machine than is usual in mining practice.

The armature shaft 19 is supported in suitable ball bearings, indicated by reference character 29,

partially recessed within the armature coils so as to keep down the height of the motor to a minimum and has an armature pinion 27 keyed on the lower end thereof.

- 5 An integral bottom portion 30 of the rearward portion 26 of the motor casing 23 is spaced downwardly from the supporting means for the bearing 29 of the armature shaft 19 and forms a slideable support for a portion of said motor. With
 10 reference to Figure 1 in particular, it may be seen that the forward edge of the integral bottom portion 30 of the rearward portion 26 of the motor casing 23 is concavely cut away adjacent the longitudinal center line of the machine to permit
 15 removal of the armature pinion 27. Said armature pinion may also be removed by splitting said motor casing and removing the armature therefrom.

A bottom plate 31 extends from the main frame 20 adjacent a forward wall thereof. Said forward wall forms a rear wall for a passageway for the cuttings discharged by the cutter chain 13, in a manner which will hereinafter be more fully explained. Said bottom plate extends rearwardly 25 to the integral bottom portion 30 of the rearward portion 26 of the motor casing 23 and is provided with a shouldered portion engaging a corresponding shouldered portion on the bottom portion 30 of the portion 26 of said motor casing. The bottom plate 31 is adapted to be detachably secured to said main frame and forward portion 24 of said motor casing by suitable holding means, such as, cap screws in a suitable manner clearly indicated in Figures 3 and 4. Thus the bottom portion 30 of the rearward portion 26 of said motor casing and bottom plate are so arranged as to permit ready accessibility to all of the parts thereunder and to keep the height of the machine down to a minimum.

- 40 Referring now in particular to the drive for the feed operating and cutter chain driving mechanism, and several other of the novel features of my invention, the armature pinion 27 meshes with and drives a spur gear 33. Said spur gear is keyed 45 on the lower end of a vertical shaft 34 journaled in suitable ball bearings adjacent the rearward end of the main frame 10. A spur pinion 35 is keyed on the upper end of the vertical shaft 34 and meshes with an idler gear 37 journaled on its 50 hub in suitable ball bearings supported in a support member 39 secured to said main frame in a suitable manner. Said idler gear is meshed with and drives a spur gear 40 keyed on the upper end of a vertical shaft 41. Said spur gear is journaled 55 on its hub in suitable ball bearings supported in a transversely extending bearing support 42. A sprocket 43 is freely mounted on the lower end of the vertical shaft 41 and is journaled on its hub in suitable ball bearings supported in said 60 main frame in a usual manner.

The sprocket 43 meshes with and drives the cutter chain 13 and suitable means are provided for operatively connecting said sprocket to the vertical shaft 41 so it may be driven thereby, 65 which means herein comprise a clutch collar 44 feathered on said vertical shaft. Said clutch collar has jaws 45 depending therefrom which are engageable with jaws 46 extending upwardly from the hub of said sprocket. Said clutch collar is 70 shifted along said vertical shaft by means of suitable clutch operating means which, as herein shown, comprise a clutch fork 47 keyed on a transversely extending rock shaft 48 and operatively connected with said clutch collar. Said trans- 75 versely extending rock shaft is operated by a

hand lever 49 disposed rearwardly of the rearward end of the main frame 10. Said hand lever is connected to said rock shaft by suitable crank and link mechanism generally indicated by reference character 50. Thus the cutter chain may 80 be selectively driven by the motor 11 in an obvious manner.

It should also be noted that the cutting mechanism is disposed forwardly of the feeding mechanism and that the cutter chain sprocket 43 and cutter chain 13 are spaced forwardly of the spur gear 33 a distance sufficient to permit the cuttings to be discharged from the retreating side of the machine forwardly of said spur gear. Such an arrangement permits the cutter bar 12 to be disposed above the spur gear 33 so as to intersect the motor 11 and effects a means for enabling the machine to be so arranged as to be of a low over-all height.

Means are provided for deflecting the cuttings 95 to the retreating side of the machine to prevent their accumulation on the advance side thereof, which means herein comprises a suitable cuttings deflector formed by a forward wall 10a of the main frame 10. Said forward wall is curved to conform 100 substantially to the path of the cutter chain 13 so said curved forward wall may cooperate with said cutter chain and aid said cutter chain in expelling the cuttings beyond the retreating side of the machine. Due to the fact that the cuttings 105 deflector is formed from the curved forward wall 10a of the main frame 10, the cuttings passageway formed therefrom is bottomless. This further aids in the disposal of the cuttings in that the cuttings cannot accumulate in the cuttings passageway 110 inasmuch as said cuttings are left behind the machine on the bottom while said machine is moving across the coal face.

Referring now in particular to the feed mechanism, the feed drum 14 is adapted to have a feed 115 rope 51 wound thereon. Said feed rope may extend forwardly from the feed drum 14 around a suitable sheave 52 to a fixed point along the mine wall for feeding the machine therealong during the cutting operation. Said feed rope may also 120 extend rearwardly from said feed drum under a suitable guide sheave 53 at the side of the machine, guide sheave 54 at the advance rearward corner of the machine, and guide sheave 55 adjacent the central portion of the machine for pulling 125 the machine onto the self-propelling truck 15. If desired, said feed rope may extend around the guide sheave 55, and a guide sheave 57 at the right hand rearward corner of the machine for summing the machine into the coal face or pulling the 130 machine in a direction opposite to its normal direction of travel.

The feed drum 14 is freely mounted on a suitable boss 58 extending outwardly from the advance wall of the main frame 10. A spur gear 59 135 is cut integral with the inner side of said feed drum and is meshed with and driven by a spur pinion 60 keyed on one end of a transversely extending shaft 61. Said transversely extending shaft is adapted to be driven by suitable frictionally controlled gear reduction mechanism which may be of any type, but which is herein preferably shown as being a gear reduction mechanism of the eccentric type, generally indicated by reference character 63.

The gear reduction mechanism 63 includes a drum 64 journaled on its hub in a suitable bearing support extending upwardly from the main frame 10 and freely mounted on a sleeve 65, which sleeve in turn is freely mounted on the transversely ex- 145 150

tending shaft 61. A worm gear 66 is keyed on the sleeve 65 for rotating said sleeve and is driven by a worm 67 cut integral with the vertical shaft 34 intermediate the ends thereof.

- 5 The frictionally controlled eccentric gear reduction mechanism 63 is of a well known type, so will only herein be described insofar as is necessary to make my invention clearly understandable. An eccentric 69 is formed integral with an 10 end of the sleeve 65 extending within the drum 64. A suitable ball bearing 70 is mounted on said eccentric, and a spur gear 71 is mounted on said ball bearing. Said spur gear in turn meshes with and drives an internal gear 72 cut integral with a 15 cage 68 journaled within the drum 64 for free rotation with respect thereto. A plurality of lugs 73 are formed integral with the spur gear 71 and have suitable blocks 74 mounted thereon for limited pivotal movement with respect thereto. 20 Said blocks are in turn slidable in suitable guides in a usual manner. When the drum 64 is held from rotation by means of a suitable friction band 75, which engages the outer periphery thereof in a usual manner, rotation of the eccentric 69 will 25 move the spur gear 71 in a non-rotatable closed orbital path which in turn will move the internal gear 72 a distance equal to the width of the number of teeth in said spur gear which engage corresponding teeth in said internal gear in a usual 30 manner well known to those skilled in the art. The speed of rotation of said internal gear is reduced by lessening the pressure of the friction band 75 on the drum 64. Likewise, said drum will slip within said friction band upon overload of 35 said internal gear to prevent damage to the feed operating parts driven thereby in a manner which will hereinafter be described.

The friction band 75 is engaged with or disengaged from the drum 64 by means of a suitable system of levers, in a usual manner, operated by a hand crank 76 threaded to a connecting rod 77 which in turn has operative connection with the friction band 75 by means of a system of cranks and levers, indicated by reference character 78. Rotation of said hand crank in one direction will engage said friction band with said drum, and rotation of said hand crank in an opposite direction will disengage said friction band from said drum in an obvious manner.

- 50 Suitable clutch means are provided for connecting the transversely extending shaft 61 with either the sleeve 65 or the internal gear 72 so said shaft may be driven at either a high speed or a slower frictionally controlled speed, which 55 means herein comprise a clutch sleeve 79 feathered on the transversely extending shaft 61. Said clutch sleeve extends within the drum 64 and has suitable clutch jaws 80 formed integral therewith. Said clutch jaws are engageable with 60 clutch jaws 81, formed integral with the cage 68 for the internal gear 72 or clutch jaws 82, formed integral with the sleeve 65. Thus when the clutch jaws 80 are engaged with the clutch jaws 81, the transversely extending shaft 61 and feed drum 64 may be driven by the internal gear 72 at a 65 slow frictionally controlled speed, and when said clutch jaws are engaged with the clutch jaws 82, said transversely extending shaft and feed drum may be driven from the sleeve 65 at a 70 higher speed.

The clutch sleeve 79 is shifted along the transversely extending shaft 61 by means of a suitable system of cranks and levers which herein comprise a clutch collar 83 engaging said clutch sleeve. Said collar is engaged by a clutch fork

84 keyed on a longitudinally extending rock shaft 85 located beneath the transversely extending shaft 61. Said rock shaft is in turn operated by means of a suitable hand lever 86 located at one side of the motor casing 23 rearwardly of the main frame 10 adjacent the retreating side thereof, and a suitable system of connecting cranks and levers in a usual manner well known to those skilled in the art.

85 It should be noted that the drive from the motor 11 is such that the speed reductions to the drum 14 may be effected in a minimum amount of space permitting said feed drum to be selectively driven from said motor at either a high speed for moving the machine along the mine bottom 90 and onto its truck in a usual manner, or at a lower frictionally controlled speed for sumping the cutter bar 12 into the coal and feeding the machine across the face of the coal.

90 Suitable means are provided for controlling and retarding the rearward end of the machine as it is being fed along the coal face by the feed drum 14 and feed rope 51, which means is herein preferably shown as being a frictionally controlled retarding drum 87 having a cable 88 wound thereon. Said retarding drum is freely mounted on a stud 89 extending rearwardly from the rearward end of the rearward portion 26 of the motor casing 23. Rotation of said retarding drum is controlled by means of a brake band 90 engageable with a suitable brake flange extending inwardly from said drum and operated by a suitable hand wheel 91 in a usual manner.

95 Suitable means are provided for driving the mining machine truck from the motor 11, which means herein comprise a spur pinion 93 keyed on the vertical shaft 41 beneath the hub of the spur gear 40. Said spur pinion meshes with and drives a spur gear 94 keyed on the upper end of a stub shaft 95 journaled intermediate its 100 ends in a suitable bearing support secured to the main frame 10. A bevel gear 96 is keyed on the lower end of the stub shaft 95 and meshes with and drives a bevel gear 97 journaled on its hub in the main frame 10 for rotation about an 105 axis extending transversely thereof. A squared socket is formed in the hub of said bevel gear. Said socket is adapted to be engaged by a squared end 98 of a coupling pin 99 having engagement with a squared inner periphery of a sleeve 100 110 journaled in a suitable support extending upwardly from the truck 15. A sprocket 101 is formed integral with the outer end of the sleeve 100 and is connected with the front track wheels 115 16 by means of a suitable chain and sprocket 102. Means are provided to hold the coupling pin 99 in engagement with the squared socket formed in the hub of the bevel gear 97, which means 120 herein comprises a member 103 pivotally supported adjacent one of its ends to one prong of a forked bracket 104 formed integral with the bearing support for the sprocket 101. The member 103 is adapted to engage the outer end of the coupling pin 99 intermediate its ends and 125 its opposite end is adapted to be detachably secured to the opposite prong of the forked bracket 104 by means of a suitable pin in the usual manner. Said coupling pin may thus be disconnected from the bevel gear 97 when it is desired to unload 130 the mining machine from its truck or be connected thereto when it is desired to move the mining machine about the mine.

135 While I have herein shown and described one form in which my invention may be embodied,

it will be understood that the construction and arrangement of the parts may be altered without departing from the spirit and scope thereof. Furthermore, I do not wish to be understood as limiting myself to the specific form of construction illustrated herein, excepting as specifically limited in the appended claims.

I claim as my invention:

1. In a mining machine, a main frame adapted to slide on its bottom on the mine bottom, a cutter bar having a cutter chain movable thereabout extending forwardly of said main frame, a motor detachably secured to the rearward end of said main frame, said motor determining the height of the machine and having a vertical armature shaft, an armature pinion on the lower end of said armature shaft and means for driving said cutter chain from said motor comprising a spur gear driven by said armature pinion and disposed in a plane so its lower surface is beneath the lower-most extremities of said cutter bar, a vertical shaft driven thereby, and another parallel vertical shaft driven from said first mentioned vertical shaft.
2. A mining machine in accordance with claim 1 wherein a cutter chain drive sprocket is mounted coaxial with said second mentioned vertical shaft and selectively connectible therewith.
3. In a mining machine, a frame adapted to slide on the mine bottom, a motor detachably secured to the rearward end of said frame substantially determining the height of the machine and having a vertical armature shaft having an armature thereon, feed mechanism therefor comprising a feed drum on one side of the machine rotatable about a horizontal transverse axis forwardly of said motor, cutting mechanism therefor comprising a cutter bar projecting forwardly of said main frame having a cutter chain guided for movement thereabout, and means for driving said feed drum and cutter chain from said motor comprising a vertical shaft located rearwardly of said feed drum, another vertical shaft located forwardly of said feed drum, a gear reduction from said motor to said first mentioned vertical shaft disposed beneath said armature and another gear reduction from said first mentioned vertical shaft to said second mentioned vertical shaft disposed adjacent the upper ends of said shafts.
4. A mining machine in accordance with claim 3 wherein a frictionally controlled gear reduction device is interposed between said first mentioned vertical shaft and said feed drum and driven therefrom by means of a worm on said first mentioned vertical shaft meshing with a worm gear directly connectible with said gear reduction device.
5. A mining machine in accordance with claim 3 wherein a frictionally controlled geared reduction device is disposed forwardly of and driven by said first mentioned vertical shaft and driven therefrom by means of a worm on said first mentioned vertical shaft meshing with a worm gear directly connectible with said geared reduction device for rotation about a transversely extending horizontal axis and wherein said geared reduction device is selectively connectible with the feed drum.
6. In combination with a room and pillar mining machine, a motor the height of which substantially determines the height of the machine, an armature shaft for said motor arranged for rotation about a vertical axis, feeding and cutting mechanism disposed forwardly of said motor comprising a feed drum rotatable about a horizontal

axis disposed transversely of said mining machine and a projecting cutter bar having a cutter chain movable thereabout, and means for driving said feeding and cutting mechanism from said motor comprising a vertical shaft driven from the lower end of said armature shaft at a reduced speed, and another vertical shaft spaced forwardly of said first mentioned vertical shaft and driven from the upper end thereof at a reduced speed.

7. A mining machine in accordance with claim 6 wherein the second mentioned vertical shaft is disposed forwardly of the feed drum and wherein in the feed drum is driven from the first mentioned vertical shaft at a relatively high traveling speed or frictionally controlled low feeding speed.

8. A mining machine in accordance with claim 6 wherein the second mentioned vertical shaft is disposed forwardly of the feed drum and has a sprocket thereon selectively connectible therewith for driving the cutter chain.

9. A mining machine in accordance with claim 6 wherein a worm is provided on the first mentioned vertical shaft and a worm gear rotatable about an axis disposed transversely of the mining machine is driven thereby, and wherein a frictionally controlled plural speed gear reduction device is driven by said worm gear and selectively connectible with the feed drum.

10. A mining machine in accordance with claim 6 wherein a worm gear rotatable about an axis disposed transversely of the machine is driven by the first mentioned vertical shaft, wherein a frictionally controlled plural speed gear reduction device is driven by said worm gear and selectively connectible with said feed drum and wherein in the second mentioned vertical shaft is disposed forwardly of said feed drum and has a sprocket selectively connectible therewith for driving the cutter chain.

11. In a mining machine, a frame, feeding mechanism therefor comprising a feed drum rotatable about a transverse axis and disposed on one side of said frame, cutting mechanism extending forwardly of said frame including a chain carrying cutter bar, and drive means for said feeding and cutting mechanism comprising a motor including a split casing detachably connectible to the rearward end of said main frame and substantially determining the height of the machine, said motor having an armature rotatable about a vertical axis, a wound field coil carried on one-half of said motor casing adjacent one side of said machine having a center coincident with a transverse vertical plane coincident with the transverse center line of said motor, a salient pole carried on the same half of said motor casing adjacent the forward end thereof having a center coincident with a longitudinal vertical plane coincident with the longitudinal center line of said motor, a wound field coil carried on the other half of said motor casing adjacent the opposite side of the machine having a center coaxial with the center of said first-mentioned wound field coil, and a salient pole carried on the same half of said motor casing adjacent the rearward end of said motor having a center coaxial with the center of said first-mentioned salient pole.

12. A mining machine in accordance with claim 11 wherein the motor casing is split in a vertical plane disposed diagonally of the frame.

13. A mining machine in accordance with claim 11 wherein the armature is provided with an armature shaft and the armature shaft has a pin-

ion keyed on the lower end thereof for driving the feeding and cutting mechanism.

14. A mining machine in accordance with claim 11 wherein means are provided for driving the feeding and cutting mechanism from the motor which comprise an armature shaft, a vertical shaft driven from the lower end thereof and another vertical shaft spaced forwardly of said first mentioned vertical shaft and driven from the upper end of said first-mentioned vertical shaft.

15. In a room and pillar mining machine slideable on its own bottom on the mine bottom, a vertically disposed motor the height of which determines the height of the machine having a motor casing divided in a vertical plane, a vertical shaft for said motor, a main frame disposed forwardly of said motor, cutting and feeding mechanism supported by said main frame including a cutter bar having a cutter chain movable thereabout extending forwardly therefrom and intersecting said motor, a cutter chain drive sprocket rotatable about a vertical axis for driving said cutter chain about said cutter bar, a feed drum disposed adjacent one side of said main frame and rotatable about an axis disposed transversely thereof rearwardly of the axis of rotation of said cutter chain sprocket, and means for driving said feeding and cutting mechanism from the lower end of said motor shaft comprising a vertical shaft disposed forwardly of said motor, gear reduction mechanism for driving said shaft from said motor, a worm on said shaft, a worm gear driven thereby and rotatable about an axis disposed transversely of said main frame, frictionally controlled plural speed gear reduction mechanism driven by said worm, means for selectively connecting said plural speed gear reduction mechanism with said feed drum, and another vertical shaft spaced forwardly of said first mentioned vertical shaft and coaxial with the axis of rotation of said cutter chain sprocket, gear reduction means for driving said second mentioned vertical shaft from said first mentioned vertical shaft and means for selectively connecting said second mentioned vertical shaft with said cutter chain drive sprocket.

16. In a room and pillar mining machine slideable on its own bottom on the mine bottom, a vertically disposed motor the height of which substantially determines the height of the machine having a vertical motor shaft with a motor pinion keyed adjacent the lower end thereof, retarding mechanism disposed rearwardly of said motor, and feeding and cutting mechanism disposed forwardly of said motor including a main frame having a cutter bar projecting forwardly therefrom having a cutter chain movable thereabout, and a feed drum disposed at one side of said main frame and rotatable about an axis disposed transversely thereof, means for driving said feed drum from said motor comprising a spur

gear driven from said motor pinion having a vertical shaft keyed thereto, means for driving said feed drum from said vertical shaft comprising a frictionally controlled gear reduction device rotatable about a transversely extending axis disposed forwardly thereof, and means for driving said cutter chain from said vertical shaft comprising a spur gear keyed thereto, an idler gear driven thereby, a spur gear driven by said idler gear, and a vertical shaft driven thereby spaced forwardly of said feed drum.

17. A mining machine in accordance with claim 16 wherein the spur gears for driving the second vertical shaft from the first vertical shaft are keyed on the upper ends of said shafts and the cutter chain is driven by a sprocket selectively connectible with said second mentioned shaft.

18. A mining machine in accordance with claim 16 wherein the cutter bar intersects the spur gear on the end of the first mentioned vertical shaft and the second mentioned shaft is spaced from the first mentioned shaft a distance greater than the sum of the radii of the spur gear on the lower end of the first mentioned shaft and the spur gear on the upper end of the second mentioned shaft.

19. In a mining machine, a frame, feeding mechanism therefor comprising a feed drum rotatable about a transverse axis and disposed on one side of said frame, cutting mechanism extending forwardly of said frame including a chain carrying cutter bar, and drive means for said feeding and cutting mechanism comprising a motor including a casing split in a vertical plane disposed diagonally of the frame and detachably connectible to the rearward end of said main frame and substantially determining the height of the machine, said motor having an armature rotatable about a vertical axis, a wound field coil carried on one-half of said motor casing adjacent one side of said machine, a salient pole carried on the same half of said motor casing adjacent the forward end thereof, a wound field coil carried on the other half of said motor casing adjacent the opposite side of the machine and a salient pole carried on the same half of said motor casing adjacent the rearward end of said motor.

20. A mining machine in accordance with claim 19, wherein the armature is provided with an armature shaft and wherein said armature shaft has a pinion keyed on the lower end thereof for driving the feeding and cutting mechanism.

21. A mining machine in accordance with claim 19, wherein means are provided for driving the feeding and cutting mechanism from the motor which comprises an armature shaft, a vertical shaft driven from the lower end thereof and another vertical shaft spaced forwardly of said first-mentioned vertical shaft and driven from the upper end of said first-mentioned vertical shaft.
